ELECTRICAL GENERATOR

Winston E. Kock and John F. Jordan, Cincinnati,
Ohio, assignors to The Baldwin Company, Cincinnati, Ohio

Application January 8, 1936, Serial No. 58,153
Renewed August 12, 1939

4 Claims. (Cl. 250—36)

In the co-pending application Serial No. 701,173 of Winston E. Kock, filed December 6, 1933, Patent No. 2,046,463 issued July 7, 1936, there was described a glow discharge oscillation generator of high stability, employing in a controlling circuit both a capacity and an inductance. In the co-pending application, Serial No. 46,449, of the same inventor, filed October 23, 1935, Patent No. 2,139,898 issued December 13, 1938, there was described an oscillating circuit having still greater stability and employing a glow discharge tube of the three element variety in which a part of the generated oscillation voltage was impressed on the grid 15 of the tube to trigger the discharge. Also in the co-pending application of said Kock, Serial No. 53,955, filed December 11, 1935, Patent No. 2,128,367 issued August 30, 1938, it has been shown that by the use of a multiplicity of 20 three electrode gas discharge tubes, it is possible to generate oscillations of related frequency in the circuits of the respective tubes, the frequency of several oscillating circuits being controlled by one master oscillator. For use, for example, in 25 an electrical organ, one of the tubes is arranged for stable oscillations at a comparatively high audio frequency. A part of the voltage of the first oscillating circuit is applied to the grid of the second tube in the series. Providing the 30 constants for the second circuit are approximately adjusted for oscillation at a harmonically related frequency, certain pulsations of the grid voltage derived from the first oscillating circuit will occur at times when the condenser for the 35 second circuit has been charged to or approximately to discharge potential. Such pulsations of the grid voltage will therefore operate to trigger the discharge of the second tube; and it will be clear that the frequency of the second oscillating circuit is fixed at a value harmonically 40 related to the frequency of the first. In a similar manner, another oscillating circuit may be related to the second and so on.

In an electrical musical instrument each of 45 the other oscillation generators in a series of this kind, are at successive octave differences to the first or master oscillation generator. In other words, each successive generator operates at a frequency half that of the preceding one, and 50 is controlled thereby. In an electrical musical instrument there will be twelve of these series of related oscillation generators; and all octave notes are accurately fixed at their proper frequencies by the respective master oscillation generators. 55

This gives a type of coordination and control in an electrical musical instrument very much superior to what is obtained when there is a separate oscillating circuit for each note in the range of the instrument, each separate oscillating circuit having stabilization control unrelated to that of any other circuit. Also because the first master oscillator in each circuit controls the frequency of those circuits connected with it, there is brought about a great simplification 19 of apparatus and the necessary mechanism can be condensed in a very much smaller space.

It is an object of the present invention to make it unnecessary to provide a separate tube for each oscillating circuit. It is also an object of our invention to provide a new type of glow discharge device adapted for the simultaneous generation of a plurality of harmonically related frequencies. These and other objects of our invention which will be set forth hereinafter, or will be apparent 20 to one skilled in the art upon reading these specifications, we accomplish by that certain construction and arrangement of parts of which we shall now describe an exemplary embodiment, both of tube and of circuit.

Reference is now made to the drawing wherein:

Fig. 1 shows somewhat diagrammatically, a special multi-electrode gas discharge tube which may be used for this purpose.

Fig. 2 indicates an exemplary circuit arrangement for the generation of a plurality of harmonically related frequencies and employing the tube of Fig. 1.

Briefly in the practice of our invention, we 35 provide a tube arranged in accordance with principles known in the art, to act as a three electrode glow discharge tube, i. e., the tube will have a cathode preferably of the indirectly heated type, a first grid to trigger the discharge, and 40 electrode means between which and the cathode the discharge may occur. Our tube differs from tubes hitherto produced however, in that there are a plurality of electrodes related not only to the cathode and the first grid, but also to each 45 other. These electrodes excepting the final ones, are in the form of grids, so that they may act individually as plates or anodes in themselves, or as grids respecting other electrodes in the series.

In the exemplary circuit, the cathode and the 50 third electrode of the series act respectively as the cathode and anode for the first oscillating circuit, the first grid acting to control the frequency of oscillations. The third electrode however can act as controlling grid for a discharge 55

circuit comprising the cathode and the fourth electrode, and so on through the series, providing the elements following the third electrode are made parts of oscillating circuits whose constants permit oscillations at frequencies harmonically related to the frequency of the first or master oscillation circuit comprising the cathode, the first grid and the third electrode.

In Fig. 1 we have shown an exemplary form 10 of glow discharge tube in which there is located within the usual envelope A, a cathode C preferably of the indirectly heated type and preferably coated with some emissive material. The leads of the various elements have been indicated in Fig. 1 by indicia corresponding to the elements themselves. If the cathode is an indirectly heated cathode, it will have filament leads 1. A first grid G is related to the cathode. To this again there is a third element P₁, which 20 is in the form of a grid but is adapted to act both as a plate respecting the first oscillating circuit and as a grid respecting other related oscillating circuits. The numbers of elements beyond this point will vary with the desired use of the 25 device. In Fig. 1 we have shown a fourth element P₂ similar to the element P₁, and a final element P₃. This last element if it is the final one of the series does not need to be of grid-like form because it does not serve as a grid for succeeding elements. It therefore may be in the 30 form of a plate. The tube will have appropriate leads and current connection means, and will also have the proper atmosphere in the envelope A for glow discharge purposes, as is known in the 35 art.

Referring to the circuit diagram, Fig. 2, the method of operation is as follows: The tube is represented as T, with C as the cathode, which may be either indirectly or directly heated, G 40 as the true grid, and P₁, P₂ as the remaining grids which are to act as plates. The final surrounding plate is indicated at P₃. The first three electrodes C, G and P₁, operate as a standard hot cathode three electrode gas 45 discharge tube, and are connected up as a grid coupled inductive glow discharge oscillator as described in the said patent of Winston E. Kock, No. 2,139,898. The frequency of these oscillations is determined by the inductance L and capacity C₁; secondary S₁ applies some of the generated voltage to the grid G and secondary S₂ furnishes the signal voltage to a circuit comprising the lead f₁. Resistance R₁ is used to set the oscillator at maximum stability.

The next electrode P₂ is connected to the circuit comprising resistance R₂ and capacity C₂ the constants of which are chosen so as to effect a discharge between the plate P₂ and cathode C at a frequency about half that of the frequency 50 of the first described oscillating circuit. Thus every other time that the discharge occurs to plate P₁ there will be a strong tendency for the discharge to extend all the way to plate P₂ provided the voltage on the condenser C₂ has built 55 up to the proper value. (R₂, the resistors which furnish a small signal voltage, have low resistance, so that the voltage on the condenser C₂ determines the voltage between plate P₂ and the cathode.) This is accomplished by selecting the 60 proper values of C₂ and R₂. In the same way R₃ and C₃ are selected to give a different sub-harmonic of the main oscillator section in a third oscillating circuit and this can be continued for as many additional signals as there are extra 65 electrodes. Each of these electrodes cannot fire

until the preceding electrode does, so that the main oscillator section controls the frequency of all the succeeding plate sections. Thus a simple means of obtaining a large number of subharmonics from one compact frequency generator is 70 produced.

It is to be understood that the circuits and method of construction shown are simply examples and that the uses and construction are not limited to those specifically shown. 10

While we have described our apparatus in connection with an exemplary use in a musical instrument, it will be understood that our invention is not confined thereto, and that the tube and the various circuits which may be used with 15 it are adapted for the generation of oscillations for any purpose for which they are desired, and also for the generation of oscillations at sub-audio and super-audio frequencies, the frequencies harmonically related. 20

Modifications may, of course, be made in the form of our tube and the disposition of its elements, but it will be noted that with respect to any series of elements C, G, P₁, P₂, etc., the elements G, P₁, etc., are not only related individually to the cathode C, but are also related to each other, so that the device is not comparable to tubes which merely have a common electrode for a plurality of discharge circuits. Were this done, there would have to be separate 30 connections, probably external of the tube between the various sets of glow discharge electrodes and controlling means therefor, and the number of elements in the tube would also be increased. While our invention does not pre- 35 ceed elements. It therefore may be in the form of a plate. The tube will have appropriate leads and current connection means, and will also have the proper atmosphere in the envelope A for glow discharge purposes, as is known in the 35 art.

Having thus described our invention, we claim:

1. An oscillation generator capable of simultaneously and separately producing a plurality of oscillations of different frequencies, said oscillation generator comprising a gas filled tube arranged to operate as a glow discharge oscillator and comprising a common cathode, a control grid and a third electrode, an oscillating circuit in which said elements are located to produce sustained oscillations of a given frequency, a fourth electrode in said tube, an oscillating circuit in which said common cathode and said fourth electrode are located to produce oscillations of a different but related frequency, said third electrode being perforated and related to 50 said fourth electrode to act as a grid therefor and to affect the discharge in said second oscillating circuit at intervals which are harmonically related to the frequency intervals of the oscillations of said first oscillating circuit. 55

2. An oscillation generator capable of producing oscillations of different but related frequencies, said oscillation generator comprising a single gas filled tube arranged to operate as a glow discharge oscillator, and comprising a common cathode, a plurality of grid structures successively related thereto and a final plate structure related to said cathode through said grid structures, a first oscillating circuit comprising said cathode and the second grid, and containing 70 capacity and inductance of values to produce oscillations at a desired frequency, said second grid acting as an anode for said oscillating circuit, and means for impressing upon the first grid variations of potential derived from said oscillat- 75

ing circuit, whereby said first grid acts as a stabilizer for said first mentioned oscillating circuit, and a plurality of additional oscillating circuits each comprising said common cathode and a successive electrode in said tube, successive grid structures excepting the first in said tube being arranged to act as an anode in one oscillating circuit and as a control grid in a succeeding oscillating circuit oscillating at a harmonically related frequency.

3. An oscillation generator capable of producing oscillations of different but related frequencies, comprising a gas filled tube arranged to operate as a glow discharge oscillator and including a common cathode, a second electrode and a third electrode related successively to said cathode, means for producing periodic glow discharges at a given frequency between said cathode and said second electrode, and a circuit including said cathode and said third electrode, arranged to produce periodic glow discharges between said cathode and said third electrode, at a frequency different from said given frequency, said second electrode being perforated and related to said third electrode so as to act as a grid therefore and to affect the discharges between said cathode and said third electrode so that they occur at a frequency which is harmonically related to said given frequency.

4. An oscillation generator capable of producing oscillations of different but related frequencies, comprising a single gas filled tube arranged to operate as a glow discharge oscillator and including a common cathode, a plurality of intermediate electrodes and a final electrode related successively to said cathode, means for producing periodic glow discharges at a given frequency between said cathode and the first of said electrodes, and a plurality of circuits including said cathode commonly and the succeeding said electrodes respectively, arranged to produce periodic glow discharges between said cathode and said succeeding electrodes respectively, at frequencies severally different from said given frequency, said intermediate electrodes being of grid-like form and arranged so that each acts as an anode for the discharges taking place between it and said cathode and acts as a grid and affects the discharges taking place between said cathode and a succeeding electrode so that the discharges between said cathode and said succeeding electrodes occur at respective frequencies which are harmonically related to said given frequency.
